EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

YARN SPOOL FOR TUBE FRAMES.

Application filed June 1, 1922. Serial No. 565,142.

To all whom it may concern:

Be it known that I, EDGAR F. HATHAWAY, a citizen of the United States, and resident of Wellesley, in the county of Norfolk and

5 State of Massachusetts, have invented certain new and useful Improvements in Yarn Spools for Tube Frames, of which the following is a specification.

This invention relates to spools such as 10 are used in tube frames to supply the filling tufts or yarn in the process of weaving pile fabrics such, for example, as Axminster carpets. Except on the narrow looms the yarn spool is usually made in two or three 15 longitudinal sections mounted in bearings on the tube frame with their adjacent journals or bearing gudgeons lying in the same bearing member which is interposed between adjacent heads of the spool sections and 20 so interlocked with each other by a tongue and groove joint or other interlocking connections as to secure uniform and equal rotation of the spool sections to obtain equal delivery of all the yarn ends as if they were 25 wound on a single integral spool.

Now as yarn ends of each spool section are trimmed before the spool is inserted in the frame in order to make them even for equal delivery to the fabric in the process 30 of weaving, it will be understood that the line of the ends of one spool section may not be registered or aligned with the yarn ends of the other spool sections when the sections are interlocked by their tongue and 35 groove joints. This condition would necessitate further trimming after the spools are inserted in the tube frame which is objectionable beside involving lost time and waste of material.

40 To overcome these difficulties I have provided one of the interlocking spool journals with the clutching connection so arranged that any spool section, after insertion in the tube frame, may be rotatably adjusted with 45 relation to the next spool section until the trimmed ends of one section are correctly aligned with the trimmed ends of the next section, thereby securing an even and equal delivery of all ends on the several spool sections and obtaining an equal tension or pull 50 on all of the ends.

This and other features of the invention will be explained in the following specification and will be defined in the claims hereto 55 annexed.

In the accompanying drawings I have illustrated different forms of construction and arrangement exemplifying the principles of this invention, in which:

Figure 1 is a plan view showing a longitudinal section of one end journal connection with its spool, the adjacent end of the next spool section being shown in dotted lines.

Figure 2 is a cross section on plane 2—2 of Figure 1.

Figure 3 is a view similar to Figure 1 showing the adjustable journal dis-engaged from clutching connection with its spool section or roller.

Figure 4 is an enlarged cross section on plane 4—4 of Figure 3.

Figures 5 and 6 are longitudinal sectional plan views showing the journal member clutched and unclutched from its yarn roller section, under a modified arrangement.

Figure 7 is an end view from the inside end of the journal connection shown in Figures 5 and 6.

In the practice of this invention any suitable form of roller section or spool may be employed. In the drawings I have shown adjacent sections *a* and *b* of the yarn spool in interlocked position in the bearing, the cylindrical portions of the two spools being indicated by dotted lines at *a* and *b* with bearing gudgeon or journals interlocked by tongue and groove engagement and seated in one of the intermediate bearings shown in dotted lines at *c*.

Inside the end of the spool body *a* is inserted a bushing or thimble 1 which may be provided with an annular groove as at 2, into which the metal tube comprising the cylinder of the tube may be spun as indicated in Figure 4. The extreme outer end of the bushing is rabbeted or turned down to allow the head or end disk 3 of the yarn spool to be pressed over it after which the edge portion of the bushing is spun up as indicated at 4 to secure the disk or head 3 firmly to the bushing to support the adjacent yarn when wound on the spool.

The object of the invention is to provide an interlocking journal or gudgeon which may be rotatably or circumferentially adjusted in relation to the spool so that, when the yarn ends of the adjacent spool sections are in register with each other, the journal may be rotated or turned without disturbing

the alignment of the yarn ends until the two adjacent journals are interlocked.

In this case the journal member is in the form of a cylindrical plug 5, provided with 5 a reduced gudgeon or journal 6, provided with either a tongue or a groove to interlock with the corresponding member of the next adjacent journal, said tongue being shown at 7 in Figure 1. The journal member, while 10 fitting snugly in the bushing, has enough freedom to permit it to slide axially of the spool. It is normally thrust outward by a yielding spring 8, abutting against its rear end, the inner end of said spring abutting 15 against the end wall 9 of the bushing. The spring surrounds a pin 10 which pin is fastened or fixed in the plug or journal member 5, and has at its outer end an enlarged head serving as a stop to limit the outward movement of said plug which results from the 20 pressure of the spring.

It will be noted that the inner wall of the bushing 1, is cut away or counterbored as shown at 12, to enlarge the internal diameter 25 of the inner end of the bushing. The plug 5 is also provided with a series of peripheral recesses 13, whose bottom faces are on the line of chords of the circumference, said recesses being of sufficient depth at their middle portions to allow bearing balls 14 to rest thereon without contact with the sub-tending inner wall of the bushing, but at their opposite ends said recesses are sufficiently shallow so that when the ball rolls toward either 30 end away from the middle position it is wedged between the bottom of the recess and the surrounding inner wall of the bushing, thus forming a ball clutch engagement. In the drawings I have shown three such recesses with their clutching balls in order 35 that in any possible rotative position of the plug at least one ball will be in clutching engagement between the plug and the bushing.

45 It will be observed, however, that when the plug is pushed inwardly so that the balls lie inside the enlarged or counterbored diameter 12 of the bushing, none of the balls will be in clutching engagement because the 50 inner wall of the bushing at this point is farther removed from even the end portions of the ball recesses than a distance equal to the diameter of the ball. In such inward position, therefore, the plug may be 55 rotated independently of the spool section, or the spool section may be rotated independently of the plug so as to secure rotative adjustment. The unclutched position is illustrated on an enlarged scale in 60 Figure 4.

65 In practice, let us suppose that the yarn spool section indicated at b in dotted lines is inserted in the open spool bearing indicated in dotted lines at c with its ends in proper position for delivery of the yarn to the

fabric to be woven. The operator then inserts the next spool section a with its interlocking member, whether a tongue 7 or a matching groove disposed at an angle to the cooperating interlocking member so as 70 to avoid allowing the tongue and groove to match and form interlocking engagement at this stage of the operation. As shown at 7^a, the ends of the tongue 7, are preferably bevelled to facilitate forcing the 75 journal plug inwardly when the spool is laid in the bearing. The parts then lie in the position indicated in Figure 4 with the journal members in non-aligned or noninterlocking position. The attendant then rotates the spool section so inserted until the 80 yarn ends are in alignment or register with the yarn ends on the adjacent spool section. After such alignment has been secured the journal is then rotated in the bushing by means of any suitable form of 85 spanner which may be inserted in the notch or groove 7^b until it is aligned with its co-operating tongue when the tension on the spring will force the tongue of the journal 90 into the groove in interlocked position. It will, therefore, be seen that with a construction operating on this principle it is no longer necessary to trim off the trimmed 95 ends of different spool sections to make them register with the yarn ends of the yarn spool sections since the circumferentially adjustable journal makes provision for bringing the yarn ends of the different 100 spool sections into register, and of securely interlocking them together by means of their journal members without disturbing such alignment.

It is, of course, immaterial whether the male or female journal member is made adjustable, and it is obvious that it is only necessary to make one of the two adjacent journal members adjustable in its spool section.

In Figures 5, 6 and 7 I have shown a 110 modified form of adjustable gripping connection for effecting the same purpose.

The form of the invention shown in Figures 5 to 7 possesses the advantage of making it possible to impart the necessary rotative movement of the connecting journal member to secure alignment between the 115 yarn ends of two adjacent spool sections by turning the disk or head which, in form above described, was secured to the bushing which is fixed inside the end of the tube 120 or roller a.

In this form of the invention I provide an internal thimble or ferrule 20 in which is placed, at its outer end, a bearing ring 21, the 125 said bearing ring, ferrule and roller tube being suitably secured together as by a screw shown at Figures 5 and 6.

Inside the bearing ring 21 is inserted a 130 rotatable sleeve 22, having at its inner end

a flange 23, to prevent endwise movement outwardly, and having its outer end rabbed so as to permit the spinning up of the thin lip at 25 over the edge of the central aperture in the disk 24, to permanently secure the disk or head 24 of the spool to the rotatable sleeve 22.

In the rear end of the bushing or ferrule 20, are mounted two semi-cylindrical clutch blocks 26 having an internal tapered bore to receive the tapered extension 34, of the journal member 30. The journal member in this case has a matching or interlocking tongue 31, which may be provided with a spanner hole 32, to permit adjustment circumferentially and is rotatably interlocked with the sleeve 22, in any suitable manner as by a spline and groove connection formed by the pin 33 and the longitudinal groove 22^a, formed in the interior wall of the sleeve 22 to permit a longitudinal sliding movement of the journal member, but to cause the journal member to rotate with the sleeve when the sleeve is rotated for adjustment in order to bring the interlocking member or tongue 31 into alignment with the matching groove in its companion journal at the end of the adjacent spool section b.

30. A compressed spring 35 normally acts to thrust the journal member outward into interlocking engagement, and this outward movement, by reason of the tapered engagement of the extension 34 with the clutch blocks 26, acts to expand such clutch blocks into peripheral gripping engagement against the inner wall of the bushing 20. Conversely the inward movement of the loose journal member releases the frictional gripping connection between the journal member and the spool section or roller to permit the circumferential adjustment of the latter and to permit the rotation of the journal member thereafter when proper alignment has been secured to interlock the two adjacent journal members and produce uniform rotation between the two spool sections.

What I claim is:

50. 1. A yarn spool for a tube frame or the like, embracing in its construction two or more spool sections having detachably interlocking journal members one of which is connected with its spool section by means of a frictional but releasable engagement to permit rotative adjustment between said spool section and its journal member in order to secure proper alignment of the yarn ends of the spool sections and also proper matching of the interlocking journal members, substantially as described.

2. A yarn spool for a tube frame or the like embracing in its construction plural spool sections and interlocking members detachably connecting the adjacent ends of the

spool sections together to secure uniform rotation of the spool sections, one member being mounted to permit circumferential adjustment between itself and its spool section in order to align the yarn ends of the 70 spool sections and allow said members to be interlocked, substantially as described.

3. A yarn spool for a tube frame embracing in its construction, plural spool sections, means for detachably connecting adjacent 75 ends of the spool sections together for uniform rotation, one of said members being circumferentially adjustable in relation to its spool section when moved inwardly in an axial direction and being operatively connected with its spool section when in outwardly extended position, substantially as described.

4. A yarn spool for a tube frame or the like embracing in its construction, plural 85 spool sections and interconnecting members arranged to detachably interlock to insure uniform rotation, one of said members being axially movable into and out of interlocking engagement with the other member and having clutched connection with its spool section when in interlocking position, said movable member being unclutched when moved out of interlocking position, substantially as described.

5. A yarn spool for a tube frame or the like embracing in its construction, plural spool sections, removably interlocked members forming end connections between the two spools to insure uniform rotation, one of 95 said members being movable into and out of interlocking position and means acting to automatically interlock said member with the cooperating end member of the adjacent spool section and thereby clutch said movable member into driving connection with its spool section, substantially as described.

6. A yarn spool for a tube frame or the like embracing in its construction, plural 100 spool sections having interconnecting end members constructed to secure uniform rotation of the sections, one of said sections being rotatable independently of its own end member to permit the alignment of its yarn ends with those of the other section while the end members are out of interlocked position, substantially as described.

7. A yarn spool for a tube frame or the like embracing in its construction, plural 105 spool sections having interlocking end members one of which is mounted to permit longitudinal movement in relation to its own spool section and also rotative movement, and a thrust spring acting to move said movable end member axially into interlocking engagement with the other end member and to frictionally clutch it to its own spool member, substantially as described.

8. A spool section for a tube frame yarn 110 spool embracing in its construction, a spool

1:
roller having yarn retaining heads, an end journal provided with means for interlocking with an end journal member of an adjacent spool, said interlocking member being axially movable into and out of frictional clutching connection with its roller, substantially as described.

9. A spool section for a yarn spool embracing in its construction a spool roller
10 having a hollow end portion, an axially movable spring-pressed member adapted to form interlocking engagement with an end member of another spool section and having clutching connection with a cooperating
15 clutch member inside said hollow end portion of the roller, said cooperating clutching member being constructed to cause the release of the clutch engagement when the spring-pressed member is moved out of its

interlocking position, substantially as described. 20

10. A spool section for a yarn spool embracing in its construction, a spool roller, a spring-pressed journal member formed to have interlocking engagement with an adjacent spool section to secure uniformity of 25 rotation of both spool sections, said journal member being provided with means to form clutching connection with its spool section when pressed outward by its spring to interlocking position and to be released from 30 said clutching connection by its inward movement away from interlocking position, substantially as described.

In witness whereof, I have subscribed the 35 above specification.

EDGAR F. HATHAWAY.
